COVER CONSTRUCTION

Franklin E. Coppock, Dayton, Ohio, assignor to Dayton Embossed Products Corporation, Dayton, Ohio, a corporation of Ohio

Application September 19, 1950, Serial No. 185,568

2 Claims. (Cl. 283—64)

1

This invention relates to a cover construction and more particularly to a cover of the type having an embossed plate built into the cover.

It is recognized that a large number of arrangements have been proposed from time to time for supporting inserts on the front cover of a book or the like, but these arrangements have either resulted in an inartistic appearance or have been so arranged that the edges of the covering material adjacent the insert readily become frayed or otherwise damaged.

It is one object of this invention to provide an improved arrangement for protecting the edges of the covering material adjacent such an insert.

It is another object of this invention to provide an improved arrangement for supporting an embossed foil covered plate, so as to largely conceal the point of juncture between the main covering and the embossed insert.

It is still another object of this invention to provide an improved cover arrangement wherein a metal foil covered board is so constructed and arranged that it serves as a protection to the adjacent surfaces of the cover.

Other objects and advantages reside in the construction of parts, the combination thereof and the mode of operation, as will become more apparent from the following description.

In the drawing:

Figure 1 is a perspective view showing my invention as applied to a book cover; and

Figure 2 is a fragmentary sectional view taken substantially on line 2—2 of Figure 1.

Referring now to the drawing wherein I have shown a preferred embodiment of my invention, reference numeral 10 generally designates a book cover and reference numeral 12 designates a specially constructed insert which is arranged as shown. The book cover 10 includes a main reinforcing element or backing member 14 which may be in the form of a piece of heavy cardboard or the like, such as commonly used in manufacturing book covers. The member 14 is substantially coextensive with the front cover of the book, whereas the embossed insert 12 covers only a portion of the front. For purpose of illustration, the embossed portion 12 has been shown as covering a major portion of the front, whereas insofar as certain aspects of the invention are concerned, it could be a much smaller insert.

The insert 12 rests against and is preferably secured to the reinforcing element 14 by some such suitable means as adhesive material, staples, or the like. Masking material 16, having a thick-

ness substantially equal to the thickness of the outer edges of the insert 12 at the point where it abuts the edges of the insert 12, surrounds the insert and has its outer periphery substantially coextensive with the outer periphery of the reinforcing element 14.

The insert 12 consists of a piece of asphalt impregnated paper board 18 having a layer of metal foil 19, such as aluminum foil, secured to its front face, as best shown in Figure 2. The embossing is done by applying heat and pressure to the metal foil coated side of the insert by means of a suitable die having a design formed therein. It will be noted that a circumferentially extending ridge 20 is formed during the embossing operation and this ridge has substantially straight side surfaces against which the edges of the outer covering material 22 fit up against after the parts have all been assembled.

By virtue of the above described ridge arrangement, it is obvious that the raw edge of the covering material 22 adjacent the insert is well protected against scuffing. Furthermore, the line of juncture between the covering material 22 and the ridge 20 is well concealed. In addition to protecting the raw edge of the outer cover 22, the ridge 20 also serves to protect the outer cover 22, as well as the embossed design or figure, against marring.

Since the embossed insert includes a metallic facing, it is obvious that the construction shown provides a very durable, as well as beautiful, cover construction. The asphalt impregnated paper board backing provides a very substantial and hard backing for the metal foil, as well as serving as an added reinforcement to the backing element 14.

As indicated in Figure 2 of the drawing, the usual finish sheet 24 is pasted or otherwise secured to the inner face of the cover, so as to provide a finished appearance.

While I have illustrated my invention as applied to a book cover, it is obvious that many aspects of the invention are equally applicable to other types of covers, such as covers for jewelry boxes and the like, wherein it is desired to provide an embossed insert surrounded by cloth, paper, or even metal. The advantage of this type of construction in making jewelry boxes and the like is that the embossing may be formed on a single flat or even curved plate which may be attached to a preformed cover element which itself could not conveniently be embossed.

Although the preferred embodiment of the device has been described, it will be understood that

within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described by invention, I claim:

1. In a book cover adapted to be bound, the combination including a substantially rectangular backing member having dimensions substantially equal to the dimensions of the book cover, an embossed insert secured to the backing member, the width and length of the embossed insert being less than the width and length of the backing member, the embossed portion of the insert being bounded by an outwardly directed rib, the outer margin of the rib extending substantially perpendicular to the backing member, masking material surrounding the insert, the thickness of the masking material in the vicinity of the insert being substantially equal to the thickness of the margin of the insert, the outer margins of the masking material being substantially coextensive with the outer margins of the backing member, an embossed sheet overlying the embossed portion of the insert, the embossed sheet being slightly larger than the embossed portion so as to extend beyond the margins of the embossed portion, means for securing the insert to the backing member, a covering material having an opening therein equal in size to the embossed portion

10
15
20

of the insert adhesively secured to the outer margin of the insert and the outer margin of the masking material, the edges of the opening of the covering material abutting the outer perpendicular margins of the rib surrounding the embossed portion so as to prevent scuffing, said covering being folded over three margins of the backing member, and a finish sheet secured to the inside of the cover and adhesively attached to the backing member and overlapping the margins of the covering material, one margin of the covering material and one margin of the finish sheet overlapping each other along the side of the book cover to be bound.

2. In a book cover according to claim 1 wherein the embossed sheet overlying the embossed area consists of a sheet of metal foil, the margins of which extend beyond the embossed area and underlie the margins of the covering material.

FRANKLIN E. COPPOCK.
